UNITED STATES PATENT OFFICE.

JAMES B. FREEMAN, OF LOS ANGELES, CALIFORNIA.

MACHINE FOR SEPARATING GOLD, SILVER, &c.

SPECIFICATION forming part of Letters Patent No. 471,731, dated March 29, 1892.

Application filed May 20, 1889. Serial No. 311,501. (No model.)

To all whom it may concern:

Be it known that I, JAMES B. FREEMAN, a citizen of the United States, residing at Los Angeles, in the county of Los Angeles and State of California, have invented new and useful Improvements in Machines for Separating Gold, Silver, and other Metals from Various other Pulverized or Granular Substances, of which the following is a full, clear, and exact description, reference being had to the accompanying drawings, forming part of this specification.

The object of my invention is the production of a machine for separating particles of gold, silver, and other metals from sand or granulated quartz and other pulverized materials of different specific gravity by the use of compressed air with organized machines, whereby the lighter constituents are separated from the metals and the latter are concentrated into a comparatively small bulk, which may be handled with economy and separated from each other by any of the known processes.

25 My invention relates to certain improvements in machines for separating ores from other substances and concentrating the former at one end of the machine, while the latter, of less gravity, are conveyed to and discharged at the opposite end of the machine, as hereinafter specified.

In the drawings, Figure 1 represents a perspective view of my improved machine. Fig. 2 is a similar view showing the opposite side 35 and end of the machine. Fig. 3 is a longitudinal central vertical section cutting the machine at a line drawn through the point denoted by O in Fig. 1. Fig. 4 represents a transverse vertical section taken at line X X 40 of Fig. 3. Fig. 5 represents a longitudinal central vertical section of the double bellows and the first compartment of the air-chambers. Fig. 6 represents a central longitudinal section of the revolving magnetic cylinder detached. Fig. 7 represents a transverse section of the same, and Fig. 8 represents a detached sectional view showing the location of a spiral spring which acts upon the guide-rolls which govern the movements of the endless apron and produce the necessary friction of the apron upon the large drum to cause it to revolve with the drum.

The frame of the main structure, consisting principally of the posts A A', with ties B B', sills and plates C C', and side boards D D', is 55 mounted with the hopper E, provided with a fluted revolving feed-roller F, driven by the belt 9, and the slide H serves to regulate the feeding from hopper E. The endless apron I, provided with transverse vertical flanges or 60 riffles upon its outer surface, is located between the side boards D D', arranged at an angle to a horizontal plane, which may be varied by vertical adjustment of its lower end, and is revolved in the direction of arrow 65 a, Fig. 3, upon drums J K L, (shown in Fig. 3,) the drum J being provided with gear M, operated through worm-gear N" on shaft O', on the opposite end of which is fixed the triplicate gear-wheel P, which is actuated by the 70 adjustable pinion Q on shaft Q', which is furnished with belt-pulley R. Endless apron I revolves around an air chest or compartment S, and is so adjusted thereto and pressed thereon at the edges of its open upper side 75 by means of set-screws T and hinged friction-rolls U (shown in Fig. 3) as to prevent air from escaping between said apron and the air-compartment. Five longitudinal bearers or slats v v' guide and support the apron and 80 prevent it from sagging by the weight of the material thereon when in use. The hinged weighted roller W aids in holding the apron I closely upon its driving and guiding drums J K L and the slats or bearers v' to prevent 85 the compressed air in compartment S (of which it forms the top or cover) from escaping between them.

The magnetic cylinder X', Figs. 6 and 7, is journaled upon the extension of the frame at 90 X below the upper or metal-discharging end of the apron I, and may be used for separating fine granulated iron from the particles of precious metals. The guide-rolls y, which press the apron by virtue of spiral springs z 95 upon the drum J, are secured upon shaft b, journaled in slots in brackets c, secured to posts A', so as to allow them sufficient vertical movement to compensate for any inequalities of the thickness of the apron which revolves under them, their purpose being to cause the apron to adhere to and revolve with the drum J. The vertical adjustment of the lower end of apron I, together with air-cham-

ber S, may be made by the screw-threaded rod d, connected to the cross-tie e at the ends of side pieces D D', which rod extends up through plate C', terminating with a hand disk or wheel f.

A pair of bellows g g' is supported by the diaphragm h in the side frame, which has journalized across its rear end the crank-shaft i, having the belt-pulley j and balance-wheel k thereon. An air-compartment l at the end of the bellows communicates therewith through valves t t and is connected by pipe n to the intermediate larger air-compartment m, which is provided with an air-tight hinged yielding top o, united thereto by the bellows-formed leather connection m'. Hinged top o is connected by a spiral spring p and adjusting-screw p' with the upright arm q, fastened to the end of air-compartment m, for the regulation of the current of air that passes through said compartment, which is thence conducted through pipe r to the interior air-chamber S. The bellows are connected for alternate operation by the rod s, Fig. 5, and are actuated by pitman u' on crank-shaft i. The respective bellows g g' are provided with air-ingress valves X'. The movement of endless apron I may be increased or decreased by means of the adjustable pinion Q and the triplicate gear-wheel P, through which and worm N and gear M the actuating-drum J is revolved to cause the revolutions of apron I. The speed of the travel of apron I requires to be regulated according to the quantity of material fed upon it to be separated. The granulated ores containing the larger percentage of metals will fill the riffles more rapidly, and therefore require that the apron should travel with greater speed. Besides, under these conditions, when metals of greater gravity are being separated from other substances, the force and pulsations of the volume of air passing from this air-compartment through the apron must be increased, and the reverse will be necessary when of less gravity, in order to separate the gross lighter substances from the metals. The traveling endless apron I is made of material of fine texture, which, while it permits the volume of air to pass up through it, resists its passage sufficiently to cause compression thereof within the air-compartments, whereby greater uniformity of action of the air is obtained. To regulate and modify the force of the current of the volume of air passing from the bellows through the air-compartments l m S, the sliding damper 2 and adjusting-screw p', which acts upon spiral spring p on the bellows-formed hinged cover o, can be used, the former to diminish the exit-orifice in compartment m and the latter to cause increase or decrease of the pulsations of the compressed air within the air chambers or compartments, which pulsations are caused by the alternating operation of the bellows g g'. Appreciating the importance of making the air-compartment S (the top of which is formed of the endless traveling apron I) com-

paratively air-tight around its upper edges, upon which the apron I is held and travels, I have provided the roller W, journalized on hinged supports N', under which the apron passes, which may have weights suspended at its ends to cause the apron to be kept in close contact with said compartment. This means, together with the mechanism shown in Fig. 3 at T U, described above, will effect the purpose mentioned.

The operation of my improved machine is as follows: Power can be applied to propel a belt 3 on pulley 6, which will communicate motion through shaft 4' and pulley 5 to belt 7, which actuates the bellows alternately through crank-shaft i, pitman u', and connecting-rod s. Pulley 8 on shaft 4' carries the belt 4, which passes over pulley R, driving the pinion Q, which in turn revolves triplicate gear-wheel P and its shaft o', with worm N'', which meshes with gear-wheel M upon the axle of drum J, which propels the apron I. The fluted feed-roller F is revolved by belt 9 on pulley 10 and the small pulley on shaft 4', and the belt 11, passing over the small pulley on shaft Q' and pulley 12 on the journal of the magnetic cylinder X', revolves said cylinder. The large belt-wheel 13 is intended to be used, if desired, to propel a fan, which may be used in connection with a trunk placed over the apron I to carry away dust which arises from the apron when the machine is in operation. The granulated material, composed of iron, gold, silver, sand, and other earthy substances, is placed in hopper E in a dry condition and discharged therefrom upon apron I by the rotation of the fluted roller F at the outlet of the hopper, the quantity being regulated by the adjustment of slide H. The inclination of the apron I and the force of the air passing up through the apron distributes the material upon the apron and causes the particles of less gravity than the metals to be raised and suspended above the apron, and at the same time slight variations of the actuating force of the volume of air will cause sufficient vibratory agitation of the suspended mass to permit the heavier constituents of the mass to separate and fill the riffles of the apron, and the elements of the mass of less gravity will be continuously buoyed up and carried down the apron and discharged at the tail of the machine, and as the apron travels in the opposite direction the metals resting upon it will be carried up by it and discharged over its more elevated end. While the apron is thus traveling with the materials to be separated upon it and suspended immediately above it, as above mentioned, the bellows will necessarily be in operation alternately, forcing air into the three air-compressing compartments l m S with a continuous but slightly intermittent power. This intermitting effect produced by the alternating action of the bellows may be modified, increased, or diminished to meet the requirements of the occasion and in ac-

cordance with the quantity of material being fed upon the apron for separation. When the cover of compartment m is forced and held down by the adjusting-screw rod p' to its lowest position, the pulsations of air will be most positive and powerful; but when the hinged top o of the air-chamber m is allowed freedom of movement its yielding capability enables it to rise and fall with the intermit- 5
ting force of the air produced by the alter-
nating action of the bellows, and the conse-
quent effect will be to diminish the vibratory
movement of the materials suspended or par-
tially suspended above the apron, as the air
10 passing through the apron from compartment
 S will be of a more uniform velocity. When
the apron I and compartment S are adjusted
by the screw-rod d , the axle of drum J in boxes
on posts A' acts as their hinged support and
15 center of motion, and the pipe r , being flexi-
ble, yields to admit such adjustment.

From the foregoing description it will be understood that although the endless apron of wire-gauze or other textile material carries the metals which fall into its riffles (being of greater gravity) up an incline to discharge them at the same time the force of the air that continuously presses in volume through the meshes of the apron causes the sand and 20 fine earthy substances which were mixed with the particles of metal to be raised up, separated from the metals, and carried over the lower end of the apron and discharged thereat.

Having described my invention, I claim
35 and desire to secure by Letters Patent—

1. In a machine for separating ores from other substances, the endless inclined adjustable revolving apron formed of textile material, through which air may be forced, in combination with three air-compartments $l m S$, the intermediate one m of which is provided

with an adjustable yielding closed cover and the primary one l is interposed between the double bellows and the air-pipe n , and flexible pipe r , provided with a sliding valve 2 to 45 regulate ingress of air to the connected air-compressing compartment S , substantially as described.

2. In a machine for separating ores from other substances, the combination of the rif- 50
fled endless revolving apron I with the drums $J K L$, gear-wheel M , worm-gear N , shaft O' , adjustable pinion Q , triplicate gear-wheel P , and intermediate driving-shaft Q' for regu- 55
lating the movements of said apron, substan-
tially as described.

3. In the above-described machine, the com- 60
bination of the endless revolving apron and its supporting-drums $J K L$, the former forming a close cover for the air-compressing com-
partment S , with adjusting set-screws T , fric-
tion-rolls U , hinged weighted roller W , and 65
apron-bearers V , as and for the purpose speci-
fied.

4. In the above-described machine, the end- 65
less revolving apron I and air-compartment S , adjustable together upon the axle of drum J , in combination with flexible pipe r and intermediate air-chamber m , pipe n , air-chamber l , and alternately-operating bellows, as and for 70
the purpose described.

5. In the above-described machine, the bel- 75
lows, the apron, the compartment S , interme-
diate air-compressing compartment m , pro-
vided with a yielding close cover, and an air-
regulating slide or valve, in combination with
adjusting devices $p p'$, as and for the purpose
specified.
